UNITED STATES PATENT OFFICE.

MILTON S. CABELL AND WILLIAM W. ABNEY, OF QUINCY, ILL., ASSIGNEES
OF ONE-THIRD TO ROBERT W. HANNA, OF SAME PLACE.

FLUID-PRESSURE REGULATOR.

SPECIFICATION forming part of Letters Patent No. 322,519, dated July 21, 1885.

Application filed May 2, 1885. (No model.)

To all whom it may concern:

Be it known that we, MILTON S. CABELL and WILLIAM W. ABNEY, citizens of the United States, residing at Quincy, in the county of Adams and State of Illinois, have invented certain new and useful Improvements in Fluid-Pressure Regulators; and we do hereby declare the following to be a full, clear, and exact description of the invention, such as will enable others skilled in the art to which it appertains to make and use the same.

Our invention relates to means for regulating the pressure of elastic fluids generated by heat; and the object of our invention is to provide automatic means for maintaining the desired pressure by regulating the heat of the furnace, the same being controlled by variations in the draft of the furnace.

To this end our invention consists in connecting with the boiler or generator a valve which may be weighted like and operated in the nature of a safety-valve, and in conducting the fluid which passes through such valve to a cylinder for operating a piston, which in turn operates through suitable connections a register or damper for varying the draft through the furnace.

Our invention also consists in certain details and special combinations, which will be hereinafter particularly described, and pointed out in the claim.

The drawing is a side view of a steam-boiler with my invention attached, partly in section and partly in elevation.

A represents the boiler; B, the smoke-stack or breeching; and D, a valve, constructed and operating like a safety-valve, arranged so that escaping steam will pass through a pipe, d, into the lower end of a cylinder, E. The valve-stem is provided with a movable head, f, which is forced upward against its seat by a spring, g, to prevent steam escaping around the stem. Cylinder E is provided with a piston, E', suitably packed. The piston-rod E" passes through a guide-box in the upper end of the cylinder and is connected with a cord, chain, or wire, F, which passes over guide-pulleys to a register, G, to which it is

fastened. The register is weighted on one side, as shown, or is provided with a spring, 5 which acts to keep it open and pulls at all times in a direction opposite to the cord.

Piston D is weighted sufficiently to overcome the spring or the weight on the register and to keep the register normally closed. A suitable pet-cock, e, is connected with the steam-passage to draw off the water of condensation. I also provide a spring, s, to cushion the piston against the head of the cylinder.

Normally the register is closed and the piston E' is down; but when the fluid in the generator reaches a pressure sufficient to open the valve the fluid passes through it and the pipe d into the cylinder E. The piston is then raised, the cord loosened, and the register opened by the weight or spring, when the air rushes into the flue and lessens the draft through the fire. When the pressure of the steam is lowered, the valve closes and the piston falls and closes the register.

We are aware that a draft-regulator has been proposed to be operated by steam escaping through the safety-valve, the cylinder in such case being provided with blow-off or exhaust-passages. This, however, fails to keep the draft closed for any effective length of time. Such we do not claim; but

What we do claim is—

A fluid-pressure regulator consisting of the combination of the boiler or generator, a valve adjustable to open at a predetermined pressure and acted upon directly by the steam in the generator, a closed cylinder, a weighted piston, a weighted register or damper, and means for connecting the damper and piston, whereby the piston is operated and the valve or damper is open and held until pressure is reduced in the boiler by reason of change of temperature in the furnace, as described.

In testimony whereof we affix our signatures in presence of two witnesses.

MILTON S. CABELL.
WILLIAM W. ABNEY.
